with the take-up heads randomly directed. A distributing device brings the empty bobbins successively from the reserve to a tilting station where the bobbins are represented horizontally. The tilting station has at its two ends, two steps arranged to retain temporarily one empty bobbin by its take-up head, so that all the bobbins leave with their take-up heads upwards. A conveyor belt carries the vertical bobbins towards the loading station of the endless conveyor.

SHEET 1 OF 3

Hig.I.

*Fig. 2.*Fig. 3. Fig. 4.

A technical line drawing of a conveyor system. On the left, a large central pulley is shown with a circular center and a flange. A belt, labeled with the number 4, runs from this pulley to the right. Along the top of the belt, there are several circular components labeled with the number 5. Below the belt, there are two sets of components labeled with the number 24. The top set consists of a small pulley and a wheel, while the bottom set consists of a larger pulley and a wheel. A belt labeled with the number 25 runs from the bottom pulley to the right. On the far right, there is a rectangular frame labeled with the number 26. The entire assembly is shown in a perspective view, with the conveyor belt running from left to right.

EMPTY BOBBIN SUPPLY DEVICES FOR A BOBBIN CHANGER FOR SPINDLE TYPE SPINNING MACHINES

The invention relates to empty bobbin supply devices for a bobbin changer for spindle type spinning machines, especially for spinning looms, stranding machines, twisting machines, etc. Such a bobbin comprises : comprises:

an endless conveyor belt arranged along each bank of the spindles and bearing gripping hooks spaced regularly at intervals corresponding to those of the spindles of the spindle bank, each of these gripping hooks being arranged to cooperate with a take-up head provided at the upper end of each bobbin,

and a loading station arranged so as to present, to each gripping hook passing at its level, the take-up head of an empty bobbin.

In such a changing apparatus, it is necessary to supply the loading station with empty bobbins throughout the duration of the operation consisting of furnishing one run of the endless belt conveyor with empty bobbins.

It is an object of the invention to provide a supply device especially adapted for a changing apparatus with an endless belt and gripping hooks.

It is another object of the invention to provide a supply device whose operation can be fully automated.

It is a further object of the invention to provide a supply device, constituted by mechanical and electrical elements, which is simple and has high operating reliability.

The supply device according to the invention takes advantage of the existence of the take-up head provided at the upper end of each empty bobbin to subject each empty bobbin to tilting which orients it in a predetermined manner.

The supply device according to the invention is characterized by the fact that it comprises in combination :

a reserve in which the empty bobbins are stacked horizontally without discrimination as to the side where their take up heads occur,

a distributing device arranged to bring empty bobbins successively from the reserve to the tilting station where these bobbins are presented horizontally, this tilting station being equipped, respectively at its two ends, with two stops arranged so as to retain provisionally one empty bobbin by its take-up head, so that all the bobbins leaving this tilting station have their take-up heads upwardly,

and a transfer device for routing the empty bobbins which have left the tilting station towards the loading station of the endless belt conveyor.

The invention will, in any case, be well understood by means of the supplementary description which follows as well as of the accompanying drawings, which supplement and drawings relate to a preferred embodiment of the invention and are of course given purely by way of illustrative and non-limiting example.

In the drawings :

FIG. 1 is a perspective view of a supply device constructed according to the invention ;

FIG. 2 is a diagrammatic and partial view of the supply device as illustrated in FIG. 1, this diagrammatic and partial view showing in simplified manner the elec-

trical connexions of the various elements of this supply device ;

FIG. 3 is a partial section and on a larger scale, of a large portion of the supply device illustrated in FIG. 1 ; and

FIG. 4 is a front view of this portion.

As shown in FIG. 1, this spinning machine is a symmetrical machine with two spindle banks 2 arranged on both sides of its longitudinal plane of symmetry.

10 The supply device of this textile machine comprises an endless belt conveyor 1 arranged along each of the two spindle banks 2, this endless belt conveyor 1 bearing gripping hooks 3 spaced regularly at intervals corresponding to those of the spindles of the spindle bank 2, each of these gripping hooks 3 being arranged to cooperate with a take-up head 4 provided at the upper end of each bobbin 5.

15 The lower portion of each gripping hook 3 has two horizontal arms, and the take-up head 4 provided at the upper end of each bobbin 5 is constituted by a cylindrical pin, coaxial with the bobbin 5, of a diameter less than the separation of the two arms of the gripping hooks 3, the said pin ending at a circular head of a diameter greater than the spacing of the two abovesaid arms.

20 A loading station 6 is then provided, preferably at one of the ends of the endless belt conveyor 1, this loading station 6 being arranged so as to present, to each gripping hook 3 passing at its level, the take-up head 4 of an empty bobbin 5.

25 The hooking of the empty bobbins 5 at the level of this loading station 6 is then operated when the endless belt conveyor 1 is actuated in such a direction — denoted by the arrow F (FIG. 1) — that the gripping hooks 3 present their open portion in the direction of this movement.

30 This loading station 6 is supplied with empty bobbins 5 by a supply device which comprises the following elements :

35 a reserve 7 in which the empty bobbins 5 are stacked horizontally without discrimination as to the side where their take-up heads 4 occur,

40 a distributing device 8 capable of bringing successively empty bobbins 5 from the reserve 7 to the tilting station 9 where these bobbins are presented horizontally, this tilting station 9 being equipped, respectively at its two ends with two stops 10 and 11 arranged so as

45 to retain provisionally an empty bobbin by its take-up head 4, so that all the bobbins arriving at the tilting station 9 are retained provisionally by their take-up heads 4 cooperating with one or other of the abovesaid stops 10 or 11 according to the orientation of the bobbin concerned which will be then subjected, by gravity, to a tilting movement around its take up-head 4 held by one or other of the stops 10 or 11 of the tilting station 9, all the bobbins leaving this tilting station 9 then being oriented in the same manner,

50 55 60 and a transfer device 12 to route the empty bobbins 5 which have left the tilting station 9 towards the loading station 6 of the conveyor 1.

The bobbins leaving the tilting station 9 therefore present all their take-up heads 4 upwardly.

65 The empty bobbins 5 presented at the tilting station 9 are positioned axially, so that the path of their take-up heads 4 encounters effectively one or other of the stops

10 or 11, by positioning means which are advantageously constituted by two centering ramps 20 and 21, situated respectively at the two ends of the tilting station 9, and cooperating with the two bases of each empty bobbin 5 to bring the bobbin into its correct axial position (FIGS. 1 and 4).

As regards the distributing device 8, it can advantageously be constituted by a scoop elevator of which the ascending run constitutes a lateral wall of the reserve 7 —wall parallel to the axis of the empty bobbins—, the tilting station 9 occurring at the upper end of the said scoop elevator, on the side of the descending run.

To facilitate removal, by gravity, of the empty bobbins leaving the tilting station 9, there are arranged at the two ends of the said tilting station 9 respectively two extraction ramps 22 and 23 cooperating with the two ends of each empty bobbin 5, the upper part of each of these extraction ramps 22 and 23 being in the neighborhood of the path of the band of the scoop elevator, whilst the lower portion of these two extraction ramps 22 and 23 occurs outside the path of the scoops of the said elevator. These scoops extend therefore only into the middle portion of the elevator since the two marginal portions must remain disengaged by reason of the presence of these two extraction ramps 22 and 23 (FIGS. 3 and 4).

It is then advantageous to arrange the descending run of the scoop elevator in oblique manner and inclined in the direction which disengages the space situated below the said tilting station 9.

To hold the empty bobbins 5 on the two extraction ramps 22 and 23, two flexible members 24 and 25 are arranged upstream of the said tilting station 9 (FIGS. 3 and 4).

The most upstream flexible member 24 is constituted by two flexible blades oriented at about 45°, each of which extends to above the tilting station 9. The least upstream flexible member 25 is constituted by two substantially vertical flexible blades, which are each slightly bent towards the extraction ramps 22 and 23 at the level of the tilting station 9. These flexible blades are fixed on the frame of the distributing device 8 by their upper end (FIG. 3).

The empty bobbin 5 occurring in the tilting station 9 will be pushed by the empty bobbin which follows it and which is itself pushed by the corresponding scoop whilst being held against the two extraction ramps 22 and 23 by the flexible member 24. The first empty bobbin 5 tilts and the second empty bobbin 5 takes its place, held against the two extraction ramps 22 and 23 by the flexible member 25.

A chute in the form of an upwardly open V is then arranged below the tilting station 9 to guide the empty bobbins 5 towards the transfer device 12 (FIGS. 1 to 4).

As regards the transfer device 12, it can advantageously be constituted by a transporter belt, provided with vertical cavities adapted to receive an empty bobbin 5, the axis AA of this transporter belt being aligned with the outer run of the endless belt conveyor 1, whilst one of the ends of this transporter belt is arranged below one of the ends of the said endless belt conveyor 1.

A loading station 6 is then constituted by the hollow of the transfer device 12 occurring on the path of the endless belt conveyor 1, each gripping hook 3 being able to hook and extract from its cavity an empty bobbin 5 (FIGS. 1 and 2).

The endless belt conveyor 1 is generally actuated by a continuous movement on the operation of hooking the empty bobbins 5 by the gripping hooks 3, and, under these conditions (FIG. 2), the distributing device 8 is driven by first motor means 27 actuated by a relay 28 servocoupled to a first detector member 29 (constituted, for example, by a micro-switch) which stops these first motor means 27 when an empty bobbin 5 has tilted in the tilting station 9, and the transfer device 12 is driven by second motor means 30 actuated by a relay 31 servocoupled to a second detector member 32 (constituted, for example, by a micro-switch) which, on one hand, stops these second motor means 30 when an empty bobbin 5 is brought to the level of the loading station 6, and which, on the other hand, restores in operation the second motor means 30 and the first motor means 27 when the empty bobbin 5 situated at the level of the loading station 6 has been hooked by a gripping hook 3 of the conveyor 1 and extracted from the vertical cavity constituting the said loading station 6.

At the level of the lower portion of the chute 26 it is preferable to arrange a third detector member 33 (constituted, for example, by a luminous source-photoelectric cell assembly) which stops the first and second motor means 27 and 30, and which stops also, through a relay 34, the third motor means 35 which drive the endless conveyor belt 1, when an empty bobbin 5 occurs accidentally blocked in the lower portion of the chute 26.

When the spinning machine comprises two spindle banks 2 as has been assumed, there is provided a single reserve 7, two distributing devices 8 arranged symmetrically on both sides of this common reserve 7, and two transfer devices 12 also arranged symmetrically with respect to this reserve 7.

These two distributing devices 8 are constituted by two scoop elevators of which the two ascending ones constitute the two lateral walls of the common reserve 7.

The bottom of the common reserve 7 has the shape of an inverted V widely open downwardly, and a fourth detector member 36 (constituted for example by a pedal actuating a micro-switch) is advantageously provided to indicate, through an alarm 37, that the common reserve no longer contains a given number of empty bobbins 5 and that it is then necessary to replenish it.

The assembly formed by the reserve 7, the two distributing devices 8 and the two transfer devices 12, constitute an assembly independent of the machine, and this assembly is mounted on rails to be displaceable, under the action of actuating means (constituted for example by one or several pneumatic jacks) between an active position, for which the two loading stations 6 occur exactly on the path of the two endless belt conveyors 1, and a resting position for which the two loading stations 6 occur withdrawn with respect to the path of the two endless belt conveyors 1, this resting position being assumed as soon as the hooking operation of the empty bobbins 5 is terminated.

The operation of the bobbin changer constructed as just described is then as follows.

Before the completion of a series of full bobbins on the two spindle banks of the machine, the endless belt conveyor is brought into its position for which it will proceed with the hooking of empty bobbins, the actuating means to bring the reserve-distributing device-transfer device assembly into its active position is operated, the motor means of the endless belt conveyor are actuated, which has the effect of causing hooking of the first empty bobbin and starting the first and second motor means of the distributing and transfer devices. The process of hooking the empty bobbins continues until the outer run of the endless belt conveyor is provided with empty bobbins, this situation being detected by suitable means which cause the arrest of the motor means of the said conveyor. The loading station remaining occupied by an empty bobbin, the first and second motor means of the distributor and transfer devices remain arrested. The reserve-distributor device-transfer device assembly is then brought back into its resting position.

In conclusion, there is provided a bobbin changing apparatus whose operation can be fully automated, this bobbin changing apparatus having a high reliability of operation since it is constituted by extremely simple mechanical and electrical elements.

Moreover, the supply device for the bobbin changer can be rendered completely independent of the machine itself, and it is possible to envisage a supply device serving several machines.

It will be understood that various changes and modifications may be made in the embodiments described and all such changes and modifications are to be regarded as within the scope of the invention as defined by the appended claims.

I claim:

1. Empty bobbin supply device for a bobbin changer for a spindle type spinning machine having at least one spindle bank, said changer comprising an endless conveyor arranged along each said spindle bank and bearing gripping hooks regularly spaced at intervals corresponding to those of the spindles of the spindle bank, each of said gripping hooks being arranged to be borne by said conveyor into engagement with a take-up head provided at the upper end of each bobbin, and a loading station arranged adjacent said conveyor so as to present the take-up head of an empty bobbin to each gripping hook passing at its level, said supply device comprising in combination:

a hopper providing a reserve in which the empty bobbins are stacked horizontally without discrimination as to the side where their take-up heads occur, a distributing device arranged to take the empty bobbins successively from said reserve, a tilting station to which the bobbins are presented horizontally by said distributing device, said tilting station being equipped, respectively at its two ends, with two stops arranged in the two possible paths of the take-up heads through the tilting station so as to retain one empty bobbin temporarily by its take-up head, so that all the empty bobbins leaving said tilting station are in an erect position in which they present their take-up heads upwardly, and a transfer device adapted to convey the empty bobbins which have left the tilting station towards

the loading station of the endless conveyor in said erect position.

2. Supply device according to claim 1, comprising two centering ramps situated respectively at the two ends of the tilting station, whereby the empty bobbins presented to the tilting station are positioned axially, said ramps cooperating with the two ends of each empty bobbin to bring said bobbins into correct axial position.

3. Supply device according to claim 1, wherein the distributing device is constituted by a scoop elevator, the ascending run of said elevator constituting one lateral wall of the reserve, and two extraction ramps are arranged at the two ends of the tilting station, said two extraction ramps cooperating with the two ends of each empty bobbin, the upper part of each of said extraction ramps being adjacent to the path of the band of the scoop elevator, whilst the lower parts of said two extraction ramps occur outside the path of the scoops of said elevator.

4. Supply device according to claim 3, including two elastic members arranged upstream of the tilting station to maintain the empty bobbins on the two extraction ramps.

5. Supply device according to claim 4, wherein the most upstream elastic member is constituted by two elastic blades oriented at about 45° which each extend up to above the tilting station, and the least upstream elastic member is constituted by two substantially vertical elastic blades which are each slightly bent towards the extraction ramps at the level of the tilting station.

6. Supply device according to claim 1, wherein the transfer device is constituted by a transporter belt provided with vertical cavities adapted to receive an empty bobbin, the axis of said transporter belt being aligned with the outer run of the endless conveyor, whilst one of the ends of said transporter belt is arranged below one of the ends of said endless conveyor.

7. Supply device according to claim 1 and adapted to cooperate with a bobbin changer in which the endless conveyor is actuated by a continuous movement on the operation of hooking the empty bobbins by the gripping hooks, wherein the distributing device is driven by first motor means coupled to a first detector member which stops the first motor means when an empty bobbin has tilted into the tilting station, and the transfer device is driven by second motor means servocoupled to a second detector member which stops said second motor means when an empty bobbin is brought to the level of the loading station, and which restores into operation the second motor means and the first motor means when the empty bobbin has been hooked by a gripping hook of the conveyor.

8. Supply device according to claim 7, wherein a third detector member is arranged below the tilting station to stop the first and second motor means and to stop also the third motor means which drive the endless conveyor, when an empty bobbin occurs accidentally blocked below said tilting station.

9. Supply device according to claim 1, adapted for a double-bank spindle type spinning machine with spindles arranged symmetrically with respect to a longitudinal plane of the machine, wherein said supply device comprises a common reserve, two distributing devices arranged symmetrically on both sides on this common

reserve, two tilting stations, and two transfer devices arranged symmetrically with respect to said common reserve and ending at two loading stations of the endless conveyors arranged along each of the two abovesaid spindle banks, the assembly formed by the common reserve, the two distributing devices, the two tilting stations and the two transfer devices constituting an assembly independent of the spinning machine, said assembly being mounted movably under the action of control means to be displaceable between an active position, for which the two loading stations occur exactly on the path of the two endless conveyors, and a resting position for which the loading stations are withdrawn with respect to said path.

10. Supply device according to claim 9, wherein the bottom of the common reserve has the form of an inverted V widely open downwardly, and a fourth detector is provided to indicate through an alarm, that the common reserve no longer contains a given number of empty bobbins and that it is then necessary to proceed with its refilling.

11. Supply device according to claim 8, adapted for a double-bank spindle type spinning machine with spindles arranged symmetrically with respect to a longitudinal plane of the machine, wherein said supply device 5 comprises a common reserve, two distributing devices arranged symmetrically on both sides on this common reserve, two tilting stations, and two transfer devices arranged symmetrically with respect to said common reserve and ending at two loading stations of the 10 endless conveyors arranged along each of the two abovesaid spindle banks, the assembly formed by the common reserve, the two distributing devices, the two tilting stations and the two transfer devices constituting an assembly independent of the spinning machine, said 15 assembly being mounted movably under the action of control means to be displaceable between an active position, for which the two loading stations occur exactly on the path of the two endless conveyors, and a resting position for which the loading stations are 20 withdrawn with respect to said path.
